SCREW AND NUT DEVICE

Leone Kamenarović, Milan, Italy, assignor to
 Fabbrica Italiana Magneti Marelli Società
 Anonima, Milan, Italy, a corporation of Italy

Application March 19, 1937, Serial No. 131,970
 In Italy March 28, 1936

6 Claims. (Cl. 74—424.8)

This invention has for its object a holder for an inductance coil having a magnetic core, particularly for high frequency electric currents, of the kind in which a section of said core is adjustable for varying the inductance value of said coil.

In known holders of the above class the adjustable section of the core is connected with the other section thereof or with supporting means for said core, by a screw engagement which provides for adjustment of said adjustable section; however objections are found in respect of the mounting of said adjustable core section because difficulties are found in securing in a simple manner, a mounting which provides for adjusting the adjustable core section without undue effort and at the same time secures a fast engagement of said section in its adjusted position.

29 In accordance with this invention the adjustable core section is screw engaged in a seat provided by screw-threaded parts which are separated from each other and are carried by yieldable members supported along edges thereof extending in a direction parallel to the axis of said seat and core section adjustable therein.

Two embodiments of the present invention are illustrated by way of example on the annexed drawing and

30 Figure 1 is a vertical section of a holder of this invention with the coil and adjustable core therein in section on line 1—1 of Fig. 3;

Figure 2 is a side elevation of said holder,
 Figure 3 is a top plan view thereof, and

35 Figure 4 is a top plan view of a modified embodiment.

In the embodiment illustrated in Figs. 1-3, said holder includes a body 1 made of insulating material and having perforated lugs 2 for fastening it on a support; said body encloses a winding 3 located within two opposite channel rings 4 and 5 which are made of a sintered ferromagnetic material and in their whole provide a hollow mantle core.

45 Hollow pillars 6 rise from the top wall 1' of the body 1. Said pillars extend substantially in the direction of the axis of the winding 3 and are arranged each in register with one vertex of a polygon having its centre on said winding axis; further said pillars are open in their region facing the winding axis, as shown at 6''.

Intermediate the pillars 6 of each pair provided by adjacent ones, laminae 7 are located; the axially extending edges of said laminae 7 are connected with adjacent edges of said hollow

pillars 6 at the sides of their open portions 6'' and said laminae are coextensive with the axis of the winding 3.

The top wall 1' of body 1 has slots 8 along the edges of said laminae 7 adjacent thereto, to make said laminae freely yieldable with respect to wall 1' and to holder body 1; said laminae 7 are provided each with a rib 7' along its middle longitudinal line and sections of a screw thread are cut in said ribs 7' the whole of the screw-threaded portions thus obtained providing a sectional nut.

An adjustable core section 9, which is made of sintered ferromagnetic material, is mounted to slide in the central bore of the mantle core 4, 15 5 and is engaged in a sleeve 10 which is screw-threaded on its outer surface and is screw-engaged in the screw-threaded portions 7' of the laminae 7; said sleeve 10 has grooves 11 for its engagement by a screw-driver.

In the described holder in view of the yielding or resilient character of the laminae 7—7' which in their whole provide a screw-threaded seat for the movable section 9—10 of the core, the said movable section may be easily adjusted with respect to the holder and mantle core 4—5 located therein; on the other hand said adjustable section 9—10 is satisfactorily fastened in any adjusted position it has been carried into because the yielding and somewhat resilient laminae 7 are supported along the extensive extent of their side edges lying in the direction of the said screwthreaded seat and they evenly engage the adjustable section 10, 9 over their screw-threaded portions, a satisfactory engagement being thus secured along the full extent of the cooperating parts.

The embodiment illustrated in Fig. 4 is similar to the above described one, but it includes only two facing screw-threaded portions 7', 7' which are provided in laminae 1; the laminae 7 are free from the transverse wall 1' of the holder 1 by effect of slots 8 therein and are supported by arcuated intermediate portions 6' connected with said top wall 1'.

The described holder conveniently consists of an integral member made of insulating material having a proper resilient or yielding material, but of course it may be made of any appropriate material and may consist of a number of separate parts properly interconnected.

What I claim as my invention and desire to secure by United States Letters Patent is:—

1. A holder for an adjustable screw threaded member, comprising a body, parts extending from

- said body parallel with and spaced from each other around an axis intermediate them, laminae each lying in a plane parallel with said axis and having edges coextensive and connected with 5 two adjacent ones of said parts, and screw-threaded means on the inner faces of said laminae providing a sectional screw-threaded seat in the space enclosed by said laminae, said seat being adapted to receive said adjustable member.
- 10 2. A holder for an adjustable screw-threaded member, comprising a body, channel section parts extending from said body parallel with and spaced from each other around an axis intermediate them, laminae each lying in a plane parallel with 15 said axis and having edges coextensive and connected with the lateral edges of two adjacent ones of said parts, and screw-threaded means on the inner faces of said laminae providing a sectional screw-threaded seat in the space enclosed by said laminae, said seat being adapted to receive said adjustable member.
- 15 3. A holder for an adjustable screw-threaded member, comprising a body, channel section parts extending from said body parallel with and spaced from each other around an axis intermediate them, said parts being open towards said intermediate axis, laminae each lying in a plane parallel with said axis and having edges coextensive and connected with the lateral edges of two adjacent ones of said parts, and screw-threaded 20 means on the inner faces of said laminae providing a sectional screw-threaded seat in the space enclosed by said laminae, said seat being adapted to receive said adjustable member.
- 25 30 4. A holder for an adjustable screw-threaded member, comprising a body, parts integral with and extending from said body parallel with and spaced from each other around an axis intermediate them, laminae separate from said body and each lying in a plane parallel with said axis and having edges coextensive and integral with two adjacent ones of said parts, and screw-threaded means on the inner faces of said laminae providing a sectional screw-threaded seat in the space enclosed by said laminae, said seat being adapted to receive said adjustable member.
- 35 5. A holder for an adjustable screw-threaded member, comprising a body, parts integral with and extending from said body parallel with and spaced from each other around an axis intermediate them, laminae separate from said body 5 and each lying in a plane parallel with said axis and having edges coextensive and integral with two adjacent ones of said parts, and screw-threaded means on the inner faces of said laminae providing a sectional screw-threaded seat in the space enclosed by said laminae, said seat being adapted to receive said adjustable member.
6. A holder for an adjustable screw-threaded member, comprising a body of insulating material, parts integral with and extending from 25 said body parallel with and spaced from each other around an axis intermediate them, laminae separate from said body and each lying in a plane parallel with said axis and having edges coextensive and integral with two adjacent ones 30 of said parts, and screw-threaded means on the inner faces of said laminae providing a sectional screw-threaded seat adapted to receive said adjustable member.
